UNITED STATES PATENT OFFICE.

ALBERT KRAUTH, OF HAMILTON, OHIO; FRITZ G. DIESBACH, ADMINISTRATOR OF SAID
ALBERT KRAUTH, DECEASED.

FOLDING MUSIC-STAND.

1,308,956.

Specification of Letters Patent. Patented July 8, 1919.

Application filed August 23, 1917. Serial No. 187,856.

To all whom it may concern:

Be it known that I, ALBERT KRAUTH, a citizen of the United States, and residing at Hamilton, in the county of Butler and State 5 of Ohio, have invented a new and useful Improvement in Folding Music-Stands, of which the following specification is a full disclosure.

My invention relates to an improvement 10 in a collapsible music stand.

An object of the invention is to provide an improved tension or friction grip for the telescoping members, constituting the vertically adjustable support for the rack.

Another object is to improve the construction 15 of the adjustable page-holder on the rack.

The features of the invention will be more fully set forth in the description of the accompanying drawings, forming a part of 20 this specification, wherein:

Figure 1 is a front elevation of the music rack.

Fig. 2 is an enlarged detail plan view on 25 line 2—2, Fig. 1.

Fig. 3 is a section on line 3—3, Fig. 2.

Fig. 4 is an enlarged elevation of the lower end of one of the telescoping rack supporting members.

Fig. 5 is an enlarged section through two 30 of the telescoping rack supporting members, showing the normal position of the friction retaining member in dotted lines.

Fig. 6 is a bottom plan view of the member shown in Fig. 4.

The adjustable stem comprises the outer and inner telescoping tube members 1, 2, vertically supported by a floor base, not shown. The upper end of member 2 supports the 40 music-rack 3, having the music-holding base ledge 4 and collapsible or lattice-like arms 5, upon which and the ledge, the music book or sheets are placed.

At one end of the inner member 2, the 45 metal of the tube is diametrically cut away, forming longitudinal slots 6. In this tube

end is riveted a short ferrule 7, having blade springs 8, springing outward radially through slots 6, before the tubes are telescoped.

These springs are first compressed into the diameter of tube 2, and then this tube is inserted into tube 1, the springs bearing frictionally against the interior peripheral surface of outer tube 1, and causing a grip, 55 sufficiently rigid to hold the parts in adjusted position and sufficiently yielding to permit of telescopic height adjustment of the rack.

Each end of the ledge 4, is rolled down- 60 wardly upon itself to form the eyes 9, extending transversely to the ledge length. In each of these eyes is swiveled an elbow tube 10, in the outer end of which is secured a wire finger 11, secured by kinking the tube 65 at 12.

This construction avoids a welding, soldering or rivet fastening. These fingers are angularly adjustable in a plane adjacent to and in front of and parallel with the arms 70 5, for holding the music on the ledge between the fingers and arms.

These constructions are cheap, strong, convenient and efficient.

Having described my invention, I claim: 75

In a music-stand, a rack comprising a base edge, the opposite ends of which are bent into transversely extending bearing eyes, collapsible arms projecting from the rear margin of the rack, an elbow tube swiveled in 80 each eye with its upper end angularly adjustable in a plane parallel with the arms, and a finger secured in each of said adjustable ends of the elbow tube.

In witness whereof, I hereunto subscribe 85 my name, as attested by the two subscribing witnesses.

ALBERT KRAUTH.

Witnesses:

GEO. W. MCGILLIARD,
ELLA CLENDENIN.
